(57) **CLAIM**

The ornamental design for bat with contoured grip, as shown and described.

DESCRIPTION

FIG. 1 is a perspective view of a bat with contoured grip invention;

FIG. 2 is a front elevational view of the bat with contoured grip, the undisclosed side being a mirror image. The broken away section is for ease of illustration;

FIG. 3 is a side elevational view of the bat with contoured grip, the broken away section is for ease of illustration;

FIG. 4 is a plan view of the bat from the butt end thereof; and,

FIG. 5 is a plan view of the bat from the head end thereof. The broken line showing of hands in FIG. 1 is for illustrative purposes only and forms no part of the claimed design.
